DUAL FIRING RATE OIL BURNER
APPARATUS

Richard M. Cochrane, West Springfield, Mass., assignor to Gilbert & Barker Manufacturing Company, Springfield, Mass., a corporation of Massachusetts

Application September 22, 1947, Serial No. 775,548

10 Claims. (Cl. 158—28)

1

This invention relates to improvements in oil burners which are adapted for house heating service and for intermittent operation at one or the other of two firing rates as may be selected manually or automatically by any suitable controlling means, to change the heating rate as changes in the weather occur.

In a burner of this type, having two oil-atomizing nozzles operable one at a time, one of the nozzles may be selected for operation and operate intermittently on and off over long periods, while the other of the nozzles remains idle. The idle nozzle contains oil which, if heated frequently, might in time carbonize and cause stoppage of the nozzle.

This invention has for one object to provide improved automatic means for frequently operating for brief periods that nozzle which is not selected for operation for the purpose of purging such nozzle of oil before it becomes carbonized. This arrangement tends to keep the idle nozzle in good condition and to avoid stoppage due to carbonization.

The invention in this respect is an improvement on that disclosed in the application of Joseph A. Logan, filed December 10, 1946, under Serial No. 715,163, and assigned to the same assignee as the present application.

The invention has for another object the provision of improved automatic means, operable in the event that either one of the nozzles, which is selected for operation, becomes inoperable because of clogging or for any other reason, to connect the other nozzle for operation in its place.

The invention in this respect is an improvement on that disclosed in the application of Joseph A. Logan, filed July 11, 1947, under Serial No. 760,396 and assigned to the same assignee as the present application.

These and other objects and advantages will best be understood in connection with the description of one illustrative example of the invention shown in the accompanying drawings, in which:

Fig. 1 is a side elevational view of an oil burner embodying the invention;

Fig. 2 is a sectional elevational view thereof;

Fig. 3 is an end elevational view with parts broken away and parts in section, showing particularly the motor, fan and pump and the control for the air inlet of the fan;

Fig. 4 is an enlarged fragmentary view of a detail connected with the air adjusting means;

Fig. 5 is a sectional plan view taken on the line 5—5 of Fig. 1;

2

Fig. 6 is a sectional view showing the mounting of one of the oil atomizing nozzles;

Fig. 7 is a fragmentary sectional elevational view taken on the line 7—7 of Fig. 5;

Fig. 8 is a fragmentary cross sectional view taken on the line 8—8 of Fig. 3;

Fig. 9 is a fragmentary cross sectional view taken on the line 9—9 of Fig. 1;

Fig. 10 is a sectional view taken on the line 10—10 of Fig. 9;

Fig. 11 is a diagrammatical view of the connections between the pump, oil atomizing nozzles, air-shutter-operating motor and control valves;

Fig. 12 is a fragmentary view showing a modification in the diagram of Fig. 11;

Fig. 13 is a diagram showing one electrical control system for the burner including means for the selection of the high or low firing rate oil atomizing nozzle and a means for actuating the unselected nozzle briefly once during each cycle of operation of the burner; and

Fig. 14 is a diagram showing a modification of the electrical control system;

Figs. 15 and 16 are diagrams showing different positions of two contact fingers shown in Fig. 14; and

Fig. 17 is a diagram showing a further modification of the electrical control system.

In these drawings, there is shown a burner of the so-called gun type, wherein air is supplied by a fan through a conduit to mix with a spray of atomized oil produced by a nozzle, located in such conduit, usually near the outlet end thereof. In Fig. 2, the air supply fan is shown at 1, mounted

in a fan housing 4, which is formed in the upper part of a casting 5, suitably supported from the floor, as by a pedestal 6. The air conduit is designated at 7. It is formed in part by an opening in the lower part of the casting 5 and in part by

a sheet metal tube 8, secured as indicated to the front end of casting 5. This tube projects forwardly and terminates with an open end surrounded by a deflector 8', which end is adapted to be inserted through the wall of the combustion chamber of a heating apparatus. The rear end of conduit 7 is closed. The fan 1 delivers air downwardly through the outlet 4' into the air conduit 7 and thence forwardly through the conduit to mix with the spray of atomized oil.

The spray of atomized oil is produced by one or the other of two oil-atomizing nozzles 9 and 10. The nozzle 10 is broken away in Fig. 2 but both nozzles are shown in Fig. 5. The nozzles 9 and 10 have supply conduits 11 and 12, which are adapted for connection one at a time to an

oil supply pump, as will later be described. Each nozzle will produce a hollow, substantially-conical, fog-like spray to mix with the air stream flowing through conduit 7. Preferably, each nozzle is of the pressure atomizing type. The nozzles have different capacities. As a single illustrative example, the nozzle 9 may have a capacity of one gallon per hour and the nozzle 10 may have a capacity of one and one-half gallons per hour.

Preferably, a so-called turbulator is provided near the outlet end of tube 8. This comprises an annulus 13 having a circular series of inwardly-projecting spiral vanes 14 which serve to whirl the air just prior to its delivery to the spray of atomized oil.

Each oil nozzle (Fig. 6) is mounted in the outer end of a hollow casing 15, which may, as shown, contain a strainer 16. These nozzle casings are mounted, as shown in Fig. 5, in holes in a bridge piece 17 and are held thereto, as by set screws 18. The two nozzles are preferably arranged with their axes in forwardly converging relation for the purpose of centralizing the oil spray, produced by each, relatively to the air conduit 7. The ends of the bridge piece 17 are mounted on two laterally-spaced, parallel rods 19 and are fixed thereto as by set screws 20. The forward ends of the rods 19 are suitably fixed as indicated, at diametrically opposite points to the annulus 13 which has a slidable engagement with the inner peripheral wall of tube 8. The rods 19 extend rearwardly through air conduit 7 and terminate with outwardly turned ends 21, adapted to engage one in each of two openings formed at diametrically opposite points in the inner peripheral wall of the air conduit near its rear end. Such end is normally closed by a plate 22, secured as indicated in Fig. 3 to member 7.

The mixture of air and oil is preferably ignited by an electric spark, produced by means later to be described, between a pair of electrodes 27. A second bridge piece 23, secured at its ends, as by set screws 24, to rods 19, supports two insulators 25, which are held in place by set screws 26. These insulators support, one in each, the electrodes 27.

The assembly of nozzles 9 and 10, the turbulator 13 and electrodes 27 may be withdrawn from the air conduit 7 as a unit for the purposes of adjustment, inspection or repair. Referring to Fig. 5, the oil conduits 11 and 12 are first disconnected at the compression couplings 11' and 12'. After plate 22 is removed, the wires are disconnected from the electrodes 27. Then the rods 19 may be drawn inwardly toward one another to withdraw the ends 21 from their openings, after which the rods may be pulled rearwardly out of conduit 7 carrying therewith the nozzles, turbulator and electrodes, all in proper working relation. The assembly may be easily replaced and the parts will be properly located in conduit 7 when the ends 21 of rods 19 are engaged in their openings. The wires are then connected to the electrodes, the oil conduits 11 and 12 reconnected and plate 22 fastened in place.

Referring next to Fig. 3, the pump which supplies oil to the atomizing nozzles is shown at 2. This pump and the fan 1 are driven by an electric motor 3. The casing of the motor 3 is suitably fixed, as indicated to one side face of the fan housing 4. In the opposite side face of this housing is the air inlet opening 28 to the fan 1. Integral with and projecting from the last-named side face are two arms 29 (Fig. 8), one on each side of the inlet 28, and the outer ends of these

arms are integrally connected by a cross bar 30, to which the oil pump 2 is secured, as by cap screws 30', with its drive shaft 31 extending toward and coaxially of the shaft 32 of the motor. The fan 1 has a hub 33 which is suitably fixed directly to shaft 32. The pump 2, however, is preferably connected to the motor shaft through the intermediary of a speed-responsive clutch, the driving and driven elements of which are indicated at 34 and 35. The driving element 34 is connected by a flexible coupling 36 to the hub 33 of fan 1 and the pump shaft 31 is fixed as indicated, to the driven clutch element 35. The clutch 34, 35 enables the motor 3 to be started up without the load of the pump 2 and enables the motor and fan to attain considerable speed before the oil pump is started. Also, on stopping, the oil pump stops before the fan and motor. The arrangement is like that of Logan Patent No. 1,985,934, granted January 1, 1935, to which reference is made for a complete disclosure of the clutch if necessary or desired.

The air inlet 28 of the fan is controlled by an air valve in the form of an annular shutter 37, (Figs. 3 and 8), the central opening of which receives the clutch elements 34 and 35. Fixed to the shutter is a nut 38 (Fig. 3) which is threaded on a screw 39. This screw has smooth cylindrical portions near its ends which portions are rotatably and slidably supported in bearings 40 and 41, respectively, located in fan housing 4 and cross bar 30. The screw is bodily movable in the direction of its axis to carry the shutter 37 from a position suitable for low firing rate operation to a position suitable for high firing rate operation. The screw has a shoulder 42 which is adapted to abut the adjacent end face of bearing 40 and limit the axially inward movement of the screw and thus define the low firing rate position of the shutter. Such position may be varied by rotating screw 39. Sliding movement of the latter in the opposite direction is limited by a second screw 43, with the inner end of which a circumferentially grooved collar 44, fixed on screw 39, is adapted to abut and define the high firing rate position of the shutter 37. The screw 43 is threaded in a nut 45, fixed to a circumferentially-flanged annular member 46, which in turn is fixed, as by screws 46', (Fig. 1) to cross bar 30. By turning the screw 43 the high firing rate position of shutter 37 may be adjusted.

The air shutter is shifted from one firing rate position to the other by means of a lever 47 (Figs. 3 and 8), the upper end of which is engaged in the groove in collar 44. This lever extends downwardly, being offset, as shown in Fig. 8, to clear the hub and shaft 31 of the pump 2, and into a groove 48 in a block 49 which is fixed, as by the cap screws 50 (Figs. 5 and 9), to the tubular lower part of the casting 5. A pin 51 fixed in the block 49 as indicated, serves as the fulcrum for the lever. The lower end of the lever 47 (Fig. 9) is pivotally connected by a pin 52 to the outer end of a piston rod 53 having on its inner end a piston 54, slidably mounted in a cylinder 55, formed by a hole drilled into one face of the block 49. An annular nut 56 is threaded in the outer end of the cylinder and slidably receives rod 53. A spring 57, coiled around the rod and acting between the nut 56 and piston 54, tends to hold the piston at the inner end of its stroke and thus the air shutter 37 in its high firing rate position. Liquid under pressure, when admitted to the inner end of the cylinder 55 will force the piston 54 outwardly, compressing spring 57 and moving lever 47 to

carry the shutter 37 into its low firing rate position.

The block 49 (Figs. 1, 3, 9 and 10) also serves to support two solenoid valves which are used to control the flow of oil to the nozzles 9 and 10 and to the motor cylinder 55. These valves, designated generally as 58 and 59, are mounted one above another in holes bored laterally through the block 49. These valves are standard articles available in the market. Each is mounted in the same way and the mounting of only one, such as 58, will be described. Valve 58 (Fig. 10) includes a cylindrical end member 60 to which is fixed one end of a tube 61, which is of non magnetic material and the other end of which has fixed to it a core 62 of magnetic material. The solenoid coil 63 encompasses the tube 61. The standard commercial form of solenoid valve includes a jacket surrounding coil 63. In this case, the jacket is removed because the block 49 will do its work. The inner end of member 60 fits into one end of the solenoid valve receiving hole in block 49 and a shoulder 64 on such end abuts block 49. A cover 65 fits over the core 62 and has a part to fit the other end of said hole in block 49 and a shoulder 66 to abut the block. A nut 67, threaded on core 62, binds the parts together, clamping the shoulders 64 and 66 against opposite faces of block 49. The latter has a vertical passage 68 (Fig. 9) therein which intersects both the valve-receiving holes which house the solenoid coils. The wires for these coils may be brought in through the passage 68 and a conduit, shown in part at 69, connected thereto. The interior of tube 61 serves as an oil chamber 70 and also as a housing for the plunger 71 of the solenoid. This plunger also serves as a valve, one of its end faces being held by a spring 72 against a valve seat 73 on the end member 60 and the opposite end face being adapted to engage a valve seat 74 on core 62 at the opposite end of the oil chamber 70, when the solenoid coil 63 is energized. The oil chamber of valve 59 is marked 75, its coil 76, its valve plunger 77 and the right and left hand valve seats as 78 and 79, respectively.

The oil pipe connections, as they are actually made, are shown in Figs. 3, 5, 9 and 10. For convenience in tracing the oil circuits and understanding the operation, these connections have also been shown diagrammatically in a single view, Fig. 11, in relation to the valves and pump and nozzles. The oil conduit 11 (Fig. 9), carrying the low firing rate nozzle 9, is connected to a passage 80 leading through the valve seat 78 of valve 59. The conduit 12 (Figs. 9 and 10), carrying the high firing rate nozzle, is connected to one end of a passage 81 (see also Fig. 1), extending through block 49, and the other end of this passage is connected by a pipe 82 (Fig. 10) to a passage 83, extending through the valve seat 74 of valve 58. A passage 84, extending through the valve seat 73 of valve 58, is connected by a pipe 85 to the oil chamber 75 of valve 59. A pipe 86 (Fig. 9) connects chamber 75 to the motor cylinder 55. A passage 87 (Fig. 10), extending through valve seat 79 of valve 59, is connected to a pipe 88, which as shown in Fig. 1, extends to the suction pipe 89 that connects pump 2 with the fuel supply tank (not shown). The outlet of pump 2 (Fig. 1) is connected to one end of a pipe 90 the other end of which as shown in Fig. 10 connects with the oil chamber 70 of valve 58.

The oil pump 2 includes a combined cut-off and pressure-regulating valve, housed within the pump casing. This valve is shown diagram-

matically in Fig. 11 by a piston 91, pressed by a spring 92 against a valve seat 93, through which extends the outlet passage, which is connected to pipe 90. Liquid is forced by pump 2 into a chamber 94 and, when this liquid reaches a predetermined minimum pressure, say 85 pounds per square inch, piston 91 is moved to the left to allow oil to flow into pipe 90. When the oil in chamber 94 attains a predetermined maximum pressure, say 100 pounds per square inch, piston 91 will be moved to the left far enough to uncover a port 95 and allow oil from chamber 94 to flow through port 95 into a chamber 96, which is connected to the suction side of pump 2. An example of one oil pump suitable for the purpose will be found in Wahlmark Patent No. 2,232,983, dated February 25, 1941, to which reference is made for a complete disclosure of the pump with its pressure-regulating and by-pass valves, if necessary or desired.

The operation of supplying fuel and air to the burner at different rates will best be understood from the diagram of Fig. 11. With both the solenoids 63 and 76 deenergized, the valves 71 and 77 will be held against the seats 73 and 78, respectively, whereby the passage 84 is closed to prevent the oil, supplied by pump 2 by way of pipe 90 to chamber 70, from flowing to chamber 75 and thence by pipe 86 to the motor cylinder 55 and also to prevent flow from chamber 75 to passage 80 and thence by pipe 11 to the low firing rate nozzle 9. Operation of the latter and the air-shutter-operating motor are thus prevented. However, the valve 71 has opened the passage 83 of valve 58 and oil, supplied by the pump to chamber 70, can flow through passage 83, pipe 82, passage 81 and pipe 12 to the high firing rate nozzle 10. At the same time, valve 77 has uncovered the passage 87 of valve 59 so that the inner end of cylinder 55 is connected by pipe 86, chamber 75, passage 87 and pipe 88 to the suction side of pump 2. The spring 57 will hold the piston 54 at the inner end of its stroke and, through lever 47, hold the air shutter 37 in proper position for high rate firing. If now, the solenoids 63 and 76 are energized in any suitable manner, and several examples will be given hereinafter, the valves 71 and 77 will be raised to engage seats 74 and 79, respectively, closing the oil passage 83, leading to the high firing rate nozzle 10, and closing the passage 87, leading to the suction side of pump 2. At the same time, the passages 84 and 80 of valves 58 and 59, respectively, will be opened. Oil, supplied by pump 2 to chamber 70, can flow by way of passage 84 and pipe 85 to chamber 75 and thence by way of passage 80 and pipe 11 to the low firing rate nozzle 9. Also, oil from chamber 75 of valve 59 can flow by way of pipe 86 into cylinder 55, thereby forcing piston 54 to the left and through lever 47 moving the air shutter 37 to proper position for low rate firing.

It will be noted that the air shutter is always in its position of greater opening, when the burner is started. The solenoids 63 and 76, as will later appear, cannot be energized until the burner motor starts. If they are then energized, as they would be for low firing rate operation, the valves 71 and 77 will open passages 84 and 80, respectively, but oil pressure will not be immediately available because the clutch elements 34 and 35 do not engage until the motor 3 and fan 1 have attained considerable speed. Therefore, the fan 1 can operate with a large air inlet opening for a short time before oil is emitted from nozzle 9 and

before oil is admitted to cylinder 55 to shift the shutter 37 to its low firing rate position. Thus, whenever the burner is set to operate at the low firing rate, and for the greater part of the heating season, it would be operating at such rate, the burner will start up with a lean mixture of air and oil which is very desirable.

Also, when the burner is stopped, while set for low firing rate operation, the solenoids 63 and 76 will be deenergized immediately when the circuit to the burner motor 3 is opened. On deenergization of the solenoids, the valves 71 and 77 will be moved with a snap action by their springs and the fuel conduit to the nozzle 9 will be closed at two places by these valves considerably before the burner cut-off valve 91 can close. An almost instantaneous, quick, sharp and double cut-off of the oil flow to the nozzle results. The motor 3 and fan 1 will coast for awhile to keep some air moving through conduit 7 but the oil flow from nozzle 9 will be stopped instantly, when the circuit to motor 3 is opened.

If the double cut-off of the oil flow to nozzle 9 is not desired, the pipe 85 can be made to connect with passage 80, as shown in Fig. 12. Then, the flow of oil to nozzle 9 will be controlled only by valve 71 and the valve 77 will be used to control the supply of oil to the motor cylinder 55. With this arrangement, on a failure of solenoid coil 76, while the burner is set for operation at a low firing rate, the burner can continue in operation but with a lean mixture because the shutter-operating cylinder 55 is cut off from the supply of pressure fluid by the closing of valve 71.

If the solenoid coil 63 fails, while the burner is set for operation at the low firing rate, the burner will operate at the high firing rate in the emergency.

As shown in Figs. 1, 3, 5, 8, 9 and 10, the block 49 with its solenoid valves 58 and 59 and some of the pipe connections are enclosed by a sheet metal hood 91. This hood (Fig. 1) is held to the lower part of casting 5 by screws 98. Fixed to the top of the hood (Fig. 8) are two clips 99 and 100. A part-cylindrical piece of sheet metal 101 (Fig. 3) encloses the space between the fan housing 4 and end member 46, resting at its ends on the flanges 102 and 103, formed on such housing and member respectively. This part 101 (Fig. 8) has along one edge an outturned lug 104 perforated to receive a hook 105 on clip 99. Along the other edge of member 101 is another lug 106, which is held by a screw 107 to clip 100. Air may enter inside the member 101 to reach the air inlet 28 by means of the space between the lower edges of the member and by means of slots in the member indicated at 101' in Figs. 1 and 8.

Since the air shutter is moved back and forth frequently by the lever 47, it is desirable that the nuts 38 and 45 be securely held to their respective screws 39 and 43. For this purpose, each nut may be constructed, as shown in Fig. 4, in two parts which have a tongue and groove engagement 108 to make them turn in unison and which are pressed apart by a spring 109. The two nut sections are thus pressed against opposite faces of the threads on the screw to provide sufficient frictional engagement between the nut sections and screw to prevent accidental turning of the nut sections due to vibration.

Referring now to the means for controlling the solenoid valves, in Fig. 13, the solenoids 63 and 76 are shown as connected in parallel and included in an electrical energizing circuit, which includes a mercury tube selector switch 110, hav-

ing terminals 111 and 112; a switch 113 which is for a purpose later to be described and which may now be assumed to be closed; and the switch 114, which controls the motor 3 and ignition means and which is closed by a room thermostat switch 115 on a demand for heat from the burner. This circuit may be traced as follows: from one supply wire 116, terminal 117, wire 118, switch 114, wire 119, terminal 120, wire 121, switch 113, contact 122, wire 123, terminal 124, wire 125, selector switch terminals 112 and 111, wire 126, solenoids 63 and 76 and wire 127 to the other supply wire 128. As shown, the selector switch 110 is set for high firing rate operation and its terminals 111 and 112 are disconnected. Consequently, when the burner is started by closing the switch 114, the solenoids 63 and 76 will not be energized and their valves 71 and 77 will remain in the illustrated positions. If the burner is to operate at the low firing rate, the tube 110 is tilted until the mercury 129 connects the terminals 111 and 112. Then, when the motor 3 is started, by the closing of switch 114, both solenoids 63 and 76 will be energized and both their valves 71 and 77 will be moved into positions for low firing rate operation.

According to some features of the invention, the selector switch 110 may be turned manually. Or, it may be turned by a thermostat, such as that conventionally indicated at 130. This thermostat may be placed at various locations as desired. As one example, it may be located outdoors and constructed to move the selector switch to high firing rate position, when the outdoor temperature is at 20° Fahr. or below, and to move the switch to low firing rate position, when the outdoor temperature is above 20° Fahr.

The circuit for the burner motor and the ignition means, will next be described. The ignition means includes a transformer having primary and secondary coils 131 and 132, respectively, the secondary coil being connected by wires 133 and 134 to the spark electrodes 27. The primary coil 131 is connected in parallel with motor 3 across a pair of wires 135 and 136 which respectively lead to the terminal 120 and the supply wire 128. On a call for heat from the burner, the room thermostat 115 causes the switch 114 to close, in a manner to be later described and a circuit is closed to motor 3 and primary 131. This circuit may be traced as follows: from supply wire 116, terminal 117, wire 118, switch 114, wire 119, terminal 120, wire 135 to the motor 3 and primary 131 and thence by wire 136 to supply wire 128.

In a burner of the kind described, where one nozzle may operate repeatedly over long intervals and the other may lay idle, the idle nozzle may become carbonized and not be operative, when it is finally selected for operation. To reduce the likelihood of trouble from this source, this invention provides means, whereby each nozzle will be used during each cycle of operation of the burner. For example, if the selector switch 110 is set for the high firing rate, then when the burner is started, the low firing rate nozzle 9 will first be operated for a short period, after which the high firing rate nozzle 10 will be brought into play. And if the burner is set for low firing rate operation, it will start up at the high firing rate and, after a brief interval, the low firing rate nozzle will be brought into action. To accomplish this an alternate energizing circuit is provided for the solenoids 63 and 76, which circuit is controlled by the described switch 113, and an auxiliary selector switch, which moves with the primary selector switch and which may be and

preferably is incorporated in the same tube, closed by the same mercury 129 and tilted by the same means. As shown, the auxiliary switch has a terminal 137 connected by a wire 137' to a terminal 138 and thence by a wire 139 to a second contact 140 of switch 113 and a terminal 142 connected to wire 126. The auxiliary selector switch operates reversely to the main selector switch and closes and opens, when the main selector switch opens and closes respectively. Accordingly, when the switch 113 is moved from contact 122 to contact 140, a circuit will be closed to the solenoids as follows: from supply wire 116, terminal 117, wire 118, switch 114, wire 119, terminal 120, wire 121, switch 113, contact 140, wire 139, terminal 138, wire 137', auxiliary selector switch terminals 137 and 142 which are connected by the mercury 129, wire 128, solenoids 63 and 76, and wire 127 back to supply wire 128. If the primary selector switch 110 is set for the low firing rate so that its terminals 111 and 112 are connected by the mercury 129, then the terminals 137 and 142 of the auxiliary selector switch are disconnected. Accordingly, when the burner starts, the switch 113 when moved to contact 140 will not energize the solenoids and the valves will remain in their high firing rate positions.

The switch 113 is arranged to close, when the room thermostat 115 closes to start the motor 3 and the ignition means, and to open when combustion at the burner has been established. Thus, on starting the burner, the switch 113 first moves to engage contact 140 and this causes the nozzle, which is not selected by the primary selector switch 110, to be operated for a moment. Then, after combustion occurs, the switch 113 moves back to engage contact 122, re-establishing the normal energizing circuit for the solenoids and causing the nozzle selected by switch 110 to operate.

To effect operation of switch 113 in the manner described, I utilize a standard form of oil burner control instrument, which is intended for use on burners, having intermittent ignition. A second contact 122 is provided for the already existing switch 113, and few wiring connections are changed. The commercial control instrument is that shown within the dot-dash rectangle. The switch 113 was originally intended to control the ignition circuit, closing it, when the contact 140 is engaged and opening it after combustion has been established. The contact 140 was originally connected to terminal 117 and the switch 113 was originally connected to terminal 138 and thence to the primary 131 of the ignition transformer. The switch 113 is part of a relay which includes three other switches 143, 144 and 145, actuated by the electromagnet 146, as indicated. This relay is actuated to close the three last-named switches and move switch 113 to engage contact 140, when the room thermostat calls for heat. After this relay is actuated, another relay is actuated almost instantly by its electromagnet 147 to close the motor switch 114 and three other switches 148, 149 and 150. After combustion occurs, a stack thermostat, shown conventionally at 151 causes a pair of contacts 152 to separate and open the circuit to electromagnet 146, whereby the first relay drops out, 70

The detailed way in which the aforesaid control operates will next be described. The room thermostat switch includes a bimetallic thermostat blade 153; two fixed contacts 154 and 155,

which are engaged successively by the blade in the order named on a demand for heat; and an electric heating coil 156, which at certain times is energized to heat blade 153 and expedite its switch opening movement. The contacts 154 and 155 are connected by wires 157 and 158 to terminals 159 and 160, respectively. The blade 153 is connected by a wire 161 to one terminal of coil 156 and the other terminal of the latter is connected by a wire 162 to a terminal 163. The terminal 159 is connected by a wire 164 to one terminal of the secondary 165 of a transformer. The other terminal of this secondary is connected by a wire 166 to one terminal of a heat-actuated time switch 167, heated by an electric heating coil 167', when the latter is energized. The other terminal of switch 167 is connected by a wire 168 to one terminal of electromagnet 146 and the other terminal of the latter is connected by a wire 169 to one of the contacts 152. The other contact 152 is connected by a wire 170 to the contact of switch 144. This last-named contact 152 is connected to one of a second pair of closed contacts 171. The other contact 171 is connected by wires 172 and 173 to one terminal of coil 167' and the other terminal of the latter is connected by wires 174 and 175 to terminal 160. A wire 176 connects wire 172 to the contact of switch 145. A wire 177 connects the contact of switch 143 to one of a pair of open contacts 178 and such contact is also connected by a wire 179 to one terminal of electromagnet 147, the other terminal of which is connected by a wire 180 to wire 168. The other contact 178 is connected by a wire 181 to the contact of switch 150. The contact of switch 149 is connected by a wire 182 to the junction of wires 174 and 175. The contact of switch 148 is connected by a wire 183 to the terminal 163. The switches 148, 149 and 150 are electrically connected as indicated at 184. So, also the switches 143, 144 and 145 are electrically connected as indicated at 185. All the switches of the two relays, except 113 and 114 are arranged in low voltage circuits supplied from the secondary 165 of a transformer 166, the primary 167 of which is connected by wires 188 and 189 to terminals 117 and 190, the latter being connected by a wire 191 to supply wire 128. The transformer is thus continuously energized.

In the operation of the control instrument described, on a demand for heat, the blade 153 makes contact first with contact 154 and then with contact 155. As soon as both contacts are engaged, a circuit to the electromagnet 146 is closed which circuit may be traced as follows: from the right hand terminal of secondary 165 by wire 164, terminal 159, wire 157, contact 154, blade 153, contact 155, wire 158, contact 160, wires 175 and 174, heat coil 167', wires 173 and 172, engaged pairs of contacts 171 and 152, wire 169, electromagnet 146, wire 168, time switch 167 and wire 166 to the other terminal of secondary 165. The electromagnet 146, being energized, the first relay pulls in, closing switches 113, 143, 144 and 145. Switch 113 will reverse the normal connections to the solenoids 63 and 76 as heretofore described, so as to actuate the unselected nozzle when the burner motor starts. The closing of switches 143 and 145 closes a circuit to the electromagnet 147 of the other relay, which circuit may be traced as follows: from the right hand terminal of secondary 165 by wire 164, terminal 159, wire 157, contact 154, blade 153, contact 155, wire 158, terminal 160, wires 175 and 174, heat coil 167', wires 173 and 176, switch 145, connec-

11

tion 185 to switch 143, switch 143, wires 177 and 179, electromagnet 147, wires 180 and 168, time switch 167 and wire 166 back to the left hand terminal of secondary 165. The switches 144 and 145 close a shunt across the contacts 171, which shunt may be traced as follows: from left hand contact 171 by wire 170, closed switch 144, connection 185, closed switch 145 and wires 176 and 172 to the right hand contact 171.

When the electromagnet 147 became energized, the second relay pulled in, closing switches 114, 148, 149 and 150. The closing of switch 114 starts the burner motor 3 and energizes the ignition transformer to produce an ignition spark across electrodes 27. Also, the solenoids 63 and 76 will be energized if the selector switch 110 is set for high firing rate operation. If combustion occurs, as it should, the stack thermostat 151 will be actuated to move the pairs of contacts 152, 171 and 178. If combustion does not occur within, say 90 seconds, the heating coil 167' will have moved the bi-metallic blade of time switch 167 to open the same, thereby opening the circuit to the electromagnets 146 and 147 and causing both relays to drop out and the motor and ignition means and solenoids 63 and 76 (if previously energized) to be deenergized.

Assuming that combustion occurs, the stack thermostat 151 will first cause the contacts 178 to engage, then the contacts 171 will be caused to disengage and finally the contacts 152 will be caused to disengage. The closing of the contacts 178 will shunt out the electric heating coil 167' and thus prevent the time switch from opening. This shunt may be traced as follows: from the upper terminal of heating coil 167', by wires 174 and 182, closed switch 149, connection 184 to switch 150, closed switch 150, wire 181 engaged contacts 178, wire 177, closed switch 143, connection 185 to switch 145, closed switch 145, and wires 176 and 173 to the lower terminal of the heating coil. An alternate circuit to electromagnet 147, excluding the heat coil 167, and the first relay, is now provided as follows: from the right hand terminal of secondary 165 by wire 164, terminal 159, wire 157, contact 156, blade 153, contact 155, wire 158, terminal 160, wires 175 and 182, closed switch 149, connection 184 to switch 150, closed switch 150, wire 181, engaged contacts 178, wire 179, electromagnet 147, wires 180 and 168, time switch 167, and wire 166 to the left hand terminal of secondary 165. The electromagnet 147 of the second relay will now remain energized after the first relay drops out. The switch 148 of the second relay closes a second and parallel branch of the holding circuit for electromagnet 147 just described. This second branch starts from switch 149, through the connection 184 to switch 148, closed switch 148, wire 183, terminal 163, wire 162, thermostat heater 156, wire 161, blade 153 to contact 155. This branch will carry practically no current because its resistance is high due to coil 156, as compared to the other branch 182, 175, 160, 158 and 155 which has extremely low resistance. However, when the other branch is opened, as later described, all the current will flow through the second branch and energize coil 156. After the stack thermostat 151 has closed the contacts 178, it opens contacts 171 but this has no immediate effect because of the closed shunt described, which maintains the circuit through switches 144 and 145. Then, the stack thermostat separates the contacts 152 and this opens the circuit to electromagnet 146 of the

12

first relay, causing it to drop out and open the switches 113, 143, 144 and 145. Switch 113 changes the circuit to solenoids 63 and 76, causing them to be energized or deenergized accordingly as the selector switch 110 is set for low or high firing rate operation, respectively. The opening of switches 144 and 145 opens the shunt across the heating coil 167' and opens the circuit thereto so that the contacts 171 when subsequently reengaged, will close a circuit to this heat coil.

The burner continues in operation with only the second relay pulled in. The circuit for the electromagnet 147 of this relay includes the engaged contacts 178. Should combustion fail, these contacts will be separated by the cooling of the stack thermostat and the circuit to electromagnet 147 will be broken, causing the second relay to drop out, opening the switch 114 to stop the motor 3 and the ignition means, and also to open the switches 148, 149, and 150. As the stack thermostat 151 continues to cool, the contacts 152 and the contacts 171 will be engaged. This occurs in about a minute after contacts 178 are separated. The contacts 152 and 171 when engaged start up the motor in the manner first described, the first relay pulling in and being followed by the pulling in of the second relay. The safety time switch 167 and its heat coil 167' are in the circuits to both these relays so that if combustion is not established in 90 seconds, the switch 167 will open and stop the burner until this switch is again closed which usually requires manual resetting. If combustion does occur the first relay will drop out as before described and the second relay only will remain pulled in.

The burner continues in operation until the demand for heat is satisfied. The initial rise in room temperature will cause the blade 153 to move to the right and disengage from contact 155 while remaining in engagement with contact 154. One branch of the circuit, including wire 158, terminal 160 and wires 175 and 182, to electromagnet 147 is thus broken and all the current must now flow through the other branch including switch 148, wire 183, terminal 163, wire 162, coil 156 and wire 161. Thus, the heating coil 156 will be energized to expedite the heating of blade 153 and the breaking of its engagement with contact 154. The arrangement is that of the customary anticipating thermostat, the burner being stopped a little before the desired room temperature is attained. This prevents the substantial overruns of temperature that frequently result when the heater 156 is not employed.

Another feature of the invention has to do with an arrangement whereby if the selected nozzle fails to operate, the other nozzle will automatically be brought into operation. Such arrangement is shown diagrammatically in Fig. 14. In this figure, the circuit to the burner motor 3 and the ignition means is the same as in Fig. 13 and it is controlled, as before, by a switch 114, closed by a relay 147 on a demand for heat from the burner, as evidenced by the room thermostat 115. The selector switch 110 and the reversing switch 113 are retained and function as before to control the solenoids 63 and 76. However, there is interposed between these solenoids and the selector switch 110 a normally-closed time switch 192, which is heat-actuated from an electric heating coil 193 and is adapted to open in a predetermined time, say 20 seconds. One terminal of switch 192 is connected

by a wire 194 to the interconnected terminals 111 and 142 of the switch 110. The other terminal of switch 192 is connected by a wire 195 to the solenoids 63 and 76. There is also provided a second and normally-open time switch 196, which is heat-actuated from an electric heating coil 197 and is adapted to close in a predetermined time, say 40 seconds. One terminal of switch 196 is connected by a wire 198 to wire 194. The other terminal of switch 196 is connected by a wire 199 to the terminal 120. The switches 192 and 196, when respectively opened and closed under the action of the heating coils 193 and 197, will be held opened and closed, respectively, by spring-actuated latches 200 and 201. The heating coil 193 has one end connected to wire 194 and has the other end connected by a wire 202 to a switch 203. The heating coil 197 has one end connected to wire 199 and has the other end connected by a wire 204 to one terminal of a switch 205. The other terminal of switch 205 is connected by a wire 207 to terminal 190 and the other terminal of switch 203 is connected by a wire 206 to the wire 207. The switches 203 and 205 are adapted to be opened by the stack thermostat 151 in a short time after combustion occurs, say 10 seconds. This stack thermostat, as before, serves to close a pair of contacts 178, then open a pair of contacts 171 and finally open a pair of contacts 152. In addition, this thermostat is made to open a pair of contacts 208. These contacts open a very short time after combustion occurs, say five seconds, and before any of the other pairs of contacts are actuated.

The switch 113 is actuated to engage contact 140 by means of the relay 146. The motor switch 114 is actuated by a relay 147, together with the switches 148, 149 and 150, but the connections are somewhat different as will now be described. One terminal of relay coil 146 is connected by a wire 209 to one terminal of the secondary 165 and the other terminal of the latter is connected by a wire 210 to the terminal 159. The other terminal of relay coil 146 is connected by a wire 211 to a spring contact finger 212 which is fixed at one end and has its contact in engagement with a spring contact finger 213, which is fixed at one end and connected by a wire 214 to one of the contacts 208. The other contact 208 is connected by wires 215, 216 and 217 to the terminal 160. Accordingly, when the room thermostat 115 calls for heat and its contacts 154 and 155 are connected by blade 153, a circuit will be closed to relay coil 146, as follows: from the right hand terminal of secondary 165 by wire 210, terminal 159, wire 157, contact 154, blade 153, contact 155, wire 158, terminal 160, wires 217, 216 and 215, engaged contacts 208, wire 214, relay coil 146 and wire 209 to the other terminal of secondary 165. This circuit will be opened, when the contacts 208 separate, shortly after combustion occurs.

One terminal of relay coil 147 is connected by a wire 218 to wire 209 and the other terminal is connected by a wire 219 to one terminal of the switch 167. The other terminal of switch 167 is connected by a wire 220 to one terminal of the heating coil 167' and the other terminal of the latter is connected by a wire 221 to one of the contacts 152. The other contact 152, which is also connected to one of the contacts 171, is connected by a wire 222 to one of the contacts 178 and the latter is connected by a wire 223 to the

contact of switch 150. The other contact 171 is connected by a wire 224 to wire 216. The other contact 178 is connected by a wire 225 to switch 167. The contact of switch 149 is connected by a wire 226 to wire 217. The contact of switch 148 is connected by a wire 227 to terminal 163.

When the room thermostat 115 calls for heat and its blade 153 connects the contacts 154 and 155, a circuit is closed to the relay coil 147. This 10 circuit may be traced as follows: from the right hand terminal of secondary 165 by wire 210, terminal 159, wire 157, contact 154, blade 153, contact 155, wire 158, terminal 160, wires 217, 216 and 224, engaged pairs of contacts 171 and 152, wire 221, heater 167', wire 220, switch 167, wire 219, relay coil 147, and wires 218 and 209 to the left hand terminal of secondary 165. Thus, the relay 147 pulls in simultaneously with the relay 146 and thereby closes the switch 114 20 to start the motor 3 and the ignition means and also closes the switches 148, 149 and 150. When the switch 150 closes, it connects with wire 223 and thus with one of the contacts 178 and, when switch 149 closes, it connects with wire 226 for 25 the purpose of establishing an alternate circuit to solenoid 147, which circuit will be completed when the contacts 178 engage, following combustion. Such circuit may be traced as follows: from the right hand terminal of secondary 165 30 by wire 210, terminal 159, wire 157, contact 154, blade 153, contact 155, wire 158, terminal 160, wires 217 and 226, closed switch 149, connection 184 to switch 150, closed switch 150, wire 223, engaged contacts 178, wire 225, switch 167, wire 219, coil 147 and wires 218 and 209 to the left 35 hand terminal of secondary 165. The closing of the described circuit by the engagement of the contacts 178 will shunt out the heater coil 167' by means of wire 221, engaged contacts 152, wire 222, engaged contacts 178 and wires 225 and 220. The circuit to heater 167' and the initial circuit to relay coil 147 will be broken, when the contacts 152 separate. The only circuit to the relay 40 147 will then be that through the engaged contacts 178. On a failure of combustion, these contacts separate very quickly and cause the relay 147 to drop out and stop the burner. On occurrence of combustion, contacts 208 disengage first in say five seconds, followed by the opening 45 of switches 203 and 205 in say 10 seconds, followed by the engagement of contacts 178, and then by the disengagement of contacts 171 and then by the disengagement of contacts 152. The closing of switch 148 closes a second and parallel branch in the circuit to the relay coil 147. This 50 branch starts at switch 150 and extends through connection 184, closed switch 148, wire 227, terminal 163, wire 162, thermostat heater 156, wire 161, and blade 153 to contact 155. This branch 55 will carry practically no current because its resistance is high due to coil 156, as compared to the other branch comprising switch 149, wires 226 and 217, terminal 160, and wire 158, which has extremely low resistance. However, when the last described branch is opened, when the thermostat blade disengages from contact 155, all the current will flow through the branch which includes coil 156, whereby the latter will heat the blade 153 and accelerate its movement to the right, causing it to disengage from contact 154 and stop the burner somewhat earlier than it would otherwise do.

The spring contact finger 212 is actuated by the relay 146. Diagrammatically, a lever 228 is 75 swung counterclockwise and clockwise, when the

relay 146 respectively pulls in and drops out and this lever through a rod 229 engages the finger 212 and controls its movement. Similarly, the relay 147 actuates a lever 230, which through a rocker arm 231, moves a rod 232 which engages the finger 213 and controls its movement. When relay 147 pulls in and drops out, the rod 232 is respectively moved to the right and the left. The arrangement is such that the contacts of the fingers 212 and 213 are engaged, as indicated, when both relays 146 and 147 are deenergized. Both spring fingers are then flexed to the left. When relays 146 and 147 are energized, the rods 229 and 232 move to the right, allowing both fingers to swing back into unflexed position, while maintaining their contacts engaged. This condition is illustrated in Fig. 15. When relay 146 drops out in response to the separation of contacts 208, the rod 229 will be moved to the left, flexing spring finger 212 to the left and carrying its contact out of engagement with the contact on finger 213. This condition is shown in Fig. 16. This arrangement provides a second break in the circuit to relay 146, whereby if the contacts 208 should engage, shortly after their separation, the relay 146 cannot be energized. When the relay 147 drops out, the rod 232 is moved to the left, flexing spring finger 213 to the left far enough to reengage its contact with the contact on finger 212. This condition is indicated in Fig. 14.

If following the energization of the relays 146 and 147 combustion does not occur, the heater 167' will in a predetermined time, say 90 seconds, cause switch 167 to open and this will open the circuit to relay 141, causing the latter to drop out and stop the burner by opening switch 114. This safety switch 167 generally has to be manually reset before the burner can operate. If the burner starts and a failure of combustion occurs later, then the stack thermostat 151 starts to cool and the first action is to separate contacts 178, which opens the circuit to relay 141 and causes immediate stopping of the burner. Continued cooling of the stack thermostat causes the contacts 208 to reengage, then the switches 203 and 205 to close, then the contacts 152 to re-engage and finally the contacts 171 to reengage. The reengagement of the pairs of contacts 171 and 152 occurs in about one minute after the contacts 178 separate and provides a scavenging period. With the room thermostat 115 still closed, the relays 146 and 147 will pull in and the burner will start up as before and, if combustion does not occur in 90 seconds, the heater 167' will open switch 167 and stop the burner until the switch 167 is manually reset.

The operation of the system shown in Fig. 14 will next be described. With the switch 110 positioned as shown, on a demand for heat from the burner, the room thermostat 115 will close, causing relays 146 and 147 to pull in, as described, and move switch 113 to contact 140 and close switch 114 to start the motor 3 and energize the ignition transformer. A circuit is established to the solenoids 63 and 76 as follows, from supply wire 116, terminal 117, wire 118, closed switch 114, wire 119, terminal 120, wire 121, switch 113, contact 140, wire 139, terminal 138, wire 137, terminal 137, mercury 129, terminal 142, wire 194, switch 192, wire 195, solenoids 63 and 76, and wire 127 back to supply wire 128. The solenoids, being energized, the low firing rate nozzle 9 is connected to operate. At the same time, the heaters 193 and 197 are connected

in the following circuits. That for heater 193 is the same as for the solenoids through wire 194 and thence it extends through heater 193 and wire 202 to switch 203, and thence by wires 208 and 207, terminal 190 and wire 191 to supply wire 128. The energizing circuit for heater 197 is as follows: from supply wire 116, terminal 117, wire 118, closed switch 114, wire 119, terminal 120, wire 199, heater 197, wire 204, switch 205, wire 207, terminal 190 and wire 191 to supply wire 128.

If combustion occurs, the contacts 208 will be separated by the stack thermostat 151 following the first relatively small rise in temperature in the stack, say in five seconds, thus opening the circuit to relay 146, which drops out causing switch 113 to engage contact 122. As relay 146 drops out, the finger 212 is moved out of engagement with finger 213. The primary energizing circuit to the solenoids is then open at switch 110, the circuit being as follows: supply wire 116, terminal 117, wire 118, closed switch 114, wire 119, terminal 120, wire 121, switch 113, contact 122, wire 123, terminal 124, wire 125, terminal 112, terminal 111, wire 194, switch 192, wire 195, solenoids 63 and 76, and wire 127 back to supply wire 128. Accordingly, the solenoids 63 and 76 will be deenergized, causing the high firing rate nozzle 10 to be connected for operation. The heater 193 will be deenergized because its circuit is open at the selector switch 110 but the heater 197 will continue to be energized. If the nozzle 10 operates, the rise in temperature, following combustion, will cause stack thermostat 151 to open the switches 203 and 205. This should occur in a few seconds after contacts 208 have separated, say from 2 to 5 seconds, or from 7 to 10 seconds following the occurrence of combustion. The heater 197 will thus be cut out of circuit, preventing switch 196 from closing. Then the contacts 178 will engage and shut out the heating coil 167', preventing the safety switch 167 from opening. Then the contacts 171 will separate and finally the contacts 152 will separate. The burner is now in running condition and will continue in operation until the room thermostat 115 opens because the demand for heat is satisfied or until a failure of combustion occurs.

If the burner shuts down in the normal way by the opening of room thermostat 115, the relay 147 will drop out, opening switch 114 to stop the motor 3 and the ignition means and opening switches 148, 149 and 150. As relay 147 drops out, it moves the finger 213 into engagement with finger 212. The contacts 178 separate very quickly as the first cooling of the burner thermostat 151 occurs. As the thermostat 151 continues to cool, the contacts 208 will be reengaged, the switches 203 and 205 will be closed, the contacts 171 and 152 will be reengaged. The burner is then in condition to be started up again on another demand for heat.

In the event that the high rate nozzle 10 fails to operate, when relay 146 drops out and shifts switch 113 back into engagement with the contact 122, combustion ceases and the burner thermostat 151 starts to cool. The contacts 208, which disengaged to cause relay 146 to drop out, will reengage very soon as the thermostat 151 cools but, since the fingers 212 and 213 are out of contact, the circuit to relay 146 cannot now be reestablished. The heater 197 will continue to heat up and in 35 seconds (assuming 5 seconds to be consumed in the starting run at the low firing rate) switch 196 will close and will be held closed by latch 201. The closing of switch 196 estab-

lishes a circuit to the solenoids 63 and 76 as follows; wire 116, terminal 117, wire 118, closed switch 114, wire 119, terminal 120, wire 199, closed switch 196, wire 198, closed switch 192, wire 195, solenoids 63 and 76, wire 127 and wire 128. The solenoids are thus energized and operate to connect the low firing rate nozzle 9 to operate. This nozzle, being operative, combustion occurs and the stack thermostat 151 opens the switches 203 and 205 and these disconnect the heaters 193 and 197. This occurs before the heater 167' has had time enough to open switch 167. Following the opening of switches 203 and 205, the contacts 178 engage and shunt out the heater 167' and finally the contacts 171 and 152 separate. The burner is now in running condition and continues in operation until the demand for heat is satisfied and the burner is stopped by the opening of the room thermostat switch 115.

On a subsequent starting of the burner, with the high rate nozzle 10 inoperative and the switch 196 locked in closed position, the burner will start up as before at the low firing rate and continue to operate at such rate. With switch 113 engaging contact 140, there will be a circuit through wire 139, terminal 138, wire 137, terminal 131, mercury 129, terminal 142, wire 194, switch 192, and wire 195 to the solenoids 63 and 76, as well as a circuit through wire 199, locked-in switch 196, wire 198, closed switch 192 and wire 195 to the solenoids. The movement of switch 113 to contact 122 will therefore not stop the energization of the solenoids and low firing rate operation will continue. If on any subsequent start the nozzle 9 fails to operate, then switch 192 will open in 20 seconds and be locked out by latch 200. This will break the circuit to the solenoids, previously established by the locked in switch 196 and connect the nozzle 10 to the pump but, since this nozzle is also inoperative, no combustion will occur and heater 167' will open switch 167 and the burner will stop in a manner such as to require manual resetting of switches 167, 192 and 196 before the burner can again be operated. While running on nozzle 9, if a failure of combustion occurs, contacts 178 will open, stopping the burner and after the one minute scavenging period, as previously described, the burner will attempt to start but will be locked out as described in the preceding sentence.

Assuming now, that, while the selector switch 110 is set, as shown, for high firing rate operation, the high firing rate nozzle 10 is operative but the low firing rate nozzle 9 is inoperative when the burner starts, the solenoids 63 and 76 will be energized through the circuit comprising wire 116, terminal 117, wire 118, closed switch 114, wire 119, terminal 120, wire 121, closed switch 113, contact 140, wire 139, terminal 138, wire 137, terminal 131, mercury 129, terminal 142, wire 194, switch 192, wire 195, solenoids 63 and 76, and wires 127 and 128. Since there is no combustion contacts 208 remain closed leaving switch 113 in engagement with contact 122 and switch 203 remains closed. The heater 193 will be energized through a circuit which is the same as that just described up to and through the wire 194 and which then extends through heater 193, wire 202, switch 203, wires 206 and 207, terminal 190 and wires 191, and 128. The heater 193 will cause switch 192 to open in 20 seconds to break the energizing circuit for the solenoids 63 and 76 and cause a shift from the low firing rate nozzle 9 to the high firing rate nozzle 10. The switch 192 locks out. The heater 197 for switch 196

started to heat up coincidentally with the heater 193 through the following circuit: wire 116, terminal 117, wire 118, closed switch 114, wire 119, terminal 120, wire 199, heater 197, wire 204, closed switch 205, wire 207, terminal 190 and wires 191 and 128. This switch 196 if actuated, would close a circuit to the solenoids and prevent high firing rate operation, but the heater 197 requires 40 seconds to actuate switch 196 so that switch 192 will open well before switch 196 can close. Meanwhile, as combustion occurs from the nozzle 10, the stack thermostat 151 opens contacts 208 to disconnect relay 146, and shortly afterward, opens the switches 203 and 205 to deenergize the heaters 193 and 197. This occurs before the contacts 178 engage. Operation of the burner at the high rate will continue, when switch 113 moves into engagement with contact 122, following the dropping out of relay 146, because there will then be no closed circuit to the solenoids 63 and 76: the circuit through terminal 122, wire 123, terminal 124 and wire 125 being broken at the terminals 111 and 112.

In the event that the high rate nozzle 10 was inoperative when the switch 192 opened, as above described, the heater 197 will in 20 seconds more cause switch 196 to close and lock in closed position but since switch 192 has been locked in open position, the circuit to the solenoids will still be open. Since there is no combustion, the thermostat 151 cannot operate any of its contacts or switches and the heater 167' continues to heat up until in 50 seconds more, it causes switch 167 to open and stop the burner.

In the case of the unsuccessful start of the low firing rate followed by successful operation at the high firing rate, following the opening of switch 192, and failure of the high rate nozzle 10 occurs during operation, then the burner will stop almost immediately when the contacts 178 open, following the first slight drop in temperature after cessation of combustion. After the one minute scavenging period, the burner will start up again. When switch 113 engages the contact 140, the circuit, which it controls to the solenoids 63 and 76, will be broken by the open and locked-out switch 192; the heater 197 will in 40 seconds cause switch 196 to close but the circuit which it controls to the solenoids is broken by the open switch 192. The heater 167' in 50 seconds more will cause switch 167 to open and stop the burner in a manner such as to require manual resetting before further operation of the burner can occur.

Assuming next that the selector switch 110 is set for low firing rate operation, being tipped in the opposite direction from that illustrated, and that the high rate nozzle 10 is operative, when the room thermostat 115 calls for heat, the relays 146 and 147 will pull in simultaneously. The fingers 212 and 213 will remain in contact. The switches 114, 148, 149 and 150 will be closed by relay 147. The switch 113 will be moved by relay 146 to engage contact 140. The energizing circuit for the solenoids 63 and 76, which circuit the switch 113 controls, is broken at the terminals 137 and 142. Accordingly the solenoids remain deenergized and the high rate nozzle 10 is connected to operate and does operate. In say five seconds after combustion occurs, the thermostat 151 causes contacts 208 to separate and relay 146 to drop out and shift switch 113 back to contact 122. Meanwhile, relay 146 has moved finger 212 out of contact with finger 213. On engagement of switch 113 with contact 122, a circuit is made to the solenoids 63 and 76 as follows: wire

116, terminal 117, wire 118, closed switch 114, wire 119, terminal 120, wire 121, switch 113, contact 122, wire 123, terminal 124, wire 125, terminal 112, mercury 129, terminal 111, wire 194, switch 192, wire 195, solenoids 63 and 76, and wires 127 and 128. The solenoids, being energized, the low rate nozzle 9 is connected for operation. If now, this nozzle 9 operates, combustion continues and the stack thermostat 151 will open switches 203 and 205 to disconnect the heaters 193 and 197 in time to prevent either time switch 192 or 196 from being actuated. Then, the contacts 178 will be engaged to shunt out the heater 167' and finally the contacts 171 and 152 will be separated and the burner will be in running condition. It will be noted that the heater 197 started warming up when switches 114 and 113 closed and that it will have been warming up for a period of about five seconds before switch 113 moves to contact 122. Accordingly, the heater 197 cannot actuate its switch 196 for 35 seconds more and long before this, the switch 205 will have been opened by the stack thermostat to disconnect the heater 197.

In the event that the nozzle 9 fails to operate, when switch 113 is moved to engage contact 122, combustion ceases and the stack thermostat 151 commences to cool. The contacts 208, which separated to cause relay 146 to drop out and shift switch 113 back to contact 122 will reengage in a short time but the fingers 212 and 213 are out of contact so that the relay 146 cannot be actuated to move switch 113 at this time. This gives time for the heater 193 to open switch 192 and break the circuit to the solenoids 63 and 76, deenergizing the latter and thereby causing the high rate nozzle 10 to be connected for operation. The switch 192 will be locked out. If this nozzle 10 operates, the burner thermostat 151 will separate the contacts 208, then open switches 203 and 205, then engage the contacts 178, then successively separate the pairs of contacts 171 and 152. The heater 167' will be shunted out and the burner placed in normal running condition, operating at the high firing rate and continuing until the demand for heat is satisfied or a failure of combustion occurs, when the burner will be stopped in the same way as heretofore described.

On a subsequent start of the burner, the high rate nozzle 10 will operate, as before, until the switch 113 is moved to contact 122 by the dropping out of relay 146, in response to the separation of contacts 208 in five seconds after occurrence of combustion. The circuit to the solenoids 63 and 76, which circuit would normally be made when switch 113 engages contact 122, is broken by the locked out switch 192, wherefore combustion continues at the high rate. The thermostat 151 will operate, as before described, until the burner is in normal running condition. Combustion continues until the demand for heat is satisfied or combustion fails, when the burner will stop in the manner heretofore described.

In the event that the low rate nozzle 9 operates successfully for a time after switch 113 is moved back to engage contact 122, following a successful five seconds run at the high firing rate, and then fails before the demand for heat is satisfied, the contacts 178 will separate, immediately stopping the burner. After the one minute scavenging period, the burner will recycle and operate at the high rate for five seconds, when the contacts 208 will be separated by the stack thermostat 151 to cause switch 113 to move back to contact 122. Combustion ceases because the low rate nozzle is inoperative and the stack thermostat cools. Since

this thermostat had not warmed up enough to engage the contacts 178, the heater 167' will still be operative and it would in 90 seconds from the closing of switch 114 open the latter and stop the burner. However, the heater 193 will in 20 seconds open switch 192, which is locked out by latch 200, breaking the circuit to the solenoids and connecting the nozzle 10 to operate and high firing rate operation will occur in time to prevent the closing of switch 196 and the opening of switch 167.

Assuming now that the high rate nozzle 10 is inoperative, when the burner is started up by the closure of room thermostat 115, the relays 146 and 147 pull in as before, closing the switches which they control. Combustion does not occur and the nozzle 10 is connected to operate but the contacts 208 remain engaged. The circuit to the solenoids, then controlled by switch 113, is open at the terminals 137 and 142 of the selector switch. The heater 193 is therefore out of circuit. However, the heater 197 is connected in the following circuit: wire 116, terminal 117, wire 118, closed switch 114, wire 119, terminal 120, wire 199, heater 197, wire 204, closed switch 205, wire 207, terminal 190, and wires 191 and 128. In 40 seconds, the switch 196 will close and become locked in closed position. This establishes a circuit to solenoids 63 and 76 as follows: wire 116, terminal 117, wire 118, closed switch 114, wire 119, terminal 120, wire 199, closed switch 196, wire 198, closed switch 192, wire 195, solenoids 63 and 76, and wires 127 and 128. The solenoids, being energized, the low rate nozzle is connected to operate. Combustion occurs, and the contacts 208 separate causing 113 to move to contact 122 and this establishes a parallel circuit to wire 194. The closing of switch 196, also closes a circuit to the heater 193, which is the same as that described up through the wire 198 and then extends as follows: heater 193, wire 202, closed switch 203, wires 206 and 207, terminal 190, and wires 191 and 128. This heater 193 requires 20 seconds to open its switch 192 and in about 10 seconds after combustion occurs, the switches 203 and 205 will be opened by the stack thermostat 151 to disconnect the heater 193. The stack thermostat then actuates the contacts 178, 171 and 152, as before described, to put the burner in normal running condition.

If the low rate nozzle 9 fails, the heater 193 will in 20 seconds open the switch 192, which becomes locked out. The circuit to the solenoids 63 and 76, is broken and the nozzle 10 is connected to operate but, since it is not operative, the failure of combustion continues and in 90 seconds after the closing of switch 114, the heater 167' will open switch 167 and stop the burner. The switches 167, 192 and 196 will have to be manually reset before the burner can again be operated.

Fig. 17 shows another control system which can be used where the feature of automatically shifting from one nozzle, which has become inoperative, to another is desired without the feature of alternately operating the nozzles during each cycle of operation of the burner. This system involves the omission of certain parts shown in Fig. 14, such as the relay 146 and its reversing switch 113, the auxiliary selector switch 131, 142 and its connections to switch 113, the contacts 208 and contact fingers 212 and 213. The relay 147 is connected to the left side of the secondary 165 by a wire 233 instead of through the two wires 209 and 218 as formerly and a supply wire 234 connects the terminal 112 of selector switch 110

21

to the wire 189. Otherwise, the parts are the same as shown in Fig. 14 and function in the same way.

The operation of the control system shown in Fig. 17 will next be described. On a demand for heat from the burner, the room thermostat 115 closes a circuit to the relay 147 as follows: from the right hand terminal of secondary 165, wire 210, terminal 159, wire 157, contact 154, blade 153, contact 155, wire 158, terminal 160, wires 217 and 224, engaged pairs of contacts 171 and 152, wire 221, heater 167', wire 220, closed switch 167, wire 219, relay coil 147, and wire 233 back to the left hand side of secondary 165. The relay 147 pulls in, closing switch 144, which starts the motor 3 and energizes the ignition transformer, and also closing switches 148, 149 and 150. The switch 114 also controls the primary energizing circuit for the solenoids 63 and 76, which circuit includes wire 116, terminal 117, wire 118, switch 114, wire 119, terminal 120, wire 199 as far as wire 234, wire 234, terminals 112 and 111 of switch 110, wire 194, time switch 192, wire 195, solenoids 63 and 76 and wires 127 and 128. This energizing circuit is now open at the terminals 111 and 112 so that the solenoids will not be energized and the high rate nozzle 10 will be connected to operate. The heater 197 of time switch 196 is energized, when switch 114 closes, through the following circuit: wire 116, terminal 117, wire 118, switch 114, wire 119, terminal 120, wire 199, heater 197, wire 204, switch 205, wire 207, terminal 190 and wires 191 and 128. If the nozzle 10 operates, combustion occurs and the stack thermostat 151 will open switch 205, in say 10 seconds, and disconnect the heater 197 and thus prevent switch 196 from closing. Also, the thermostat 151 will, as before, cause contacts 178 to engage and then cause the pairs of contacts 171 and 152 to successively separate. The heater 167' will be shunted out, when contacts 178 engage, and the burner placed in normal running condition as before.

If, when the switch 114 was closed to start the burner, the nozzle 10 failed to operate, there would be no combustion and the stack thermostat 151 would not open switch 205. Accordingly, the heater 197 would continue to be energized and it would in a predetermined time, say 40 seconds, cause switch 196 to close and become locked in by the latch 201. An alternate energizing circuit to the solenoids would then be closed as follows: wire 116, terminal 117, wire 118, closed switch 114, wire 119, terminal 120, wire 199, closed switch 196, wire 198, closed switch 192, wire 195, solenoids 63 and 76, and wires 127, and 128. The solenoids will be energized and cause nozzle 9 to be connected to operate. When the switch 114 is closed, it closes a circuit to the heater 193 which is the same as the last-named circuit up through the wire 198 and thence extends by heater 193, wire 202, closed switch 203, wires 206 and 207, terminal 190 and wires 191 and 128. If the nozzle 9 operates, the stack thermostat will function as before and open switch 203 before heater 193 can open switch 192 and the burner will operate at the low rate in the emergency. If the nozzle 9 does not operate, the heater 193 will in 20 seconds more cause switch 192 to open and become locked out by latch 200, opening the circuit to the solenoids and causing the nozzle 10 to be connected to operate. Since the nozzle 10 is inoperative, combustion does not occur and in 30 seconds more the heater 167' will cause switch 167 to open and stop the burner in such a way as to require manual resetting of switches 167, 192 and 196. Should

22

the nozzle 10 fail during a normal run of the burner instead of at the starting of the burner, then contacts 178 will be separated by thermostat 151 soon after combustion failure. The burner will stop and, after the one minute scavenging period, it will automatically start up again and then the heater 197 will be energized and in 40 seconds close switch 196, as before described to render the low rate nozzle 9 operative.

Assume now that the selector switch 110 is set for low rate firing, being tipped in the opposite direction from that shown. Then, the mercury 120 will connect the terminals 111 and 112, whereby when switch 114 is closed, the described primary energizing circuit for the solenoids will be closed and nozzle 9 be connected to operate. The heaters 193 and 197 will both be energized when switch 114 closes, through the circuits already described. If nozzle 9 operates, the switches 203 and 205 will operate before the heaters 193 and 197 can actuate their respective switches 192 and 196 and the heater 167' will be shunted out to prevent the opening of switch 167. If nozzle 9 fails to operate, the switches 203 and 205 will not be opened by the stack thermostat 151 and in 20 seconds the heater 193 will cause switch 192 to open and break the primary energizing circuit to the solenoids, causing the nozzle 10 to be connected to operate. Switch 192 is locked out by latch 200. If nozzle 10 operates, the thermostat 151 will open switch 205 to disconnect heater 197 and prevent it from closing switch 198. Also, heater 167' will be shunted out as before described. If nozzle 10 fails to operate, the heater 167' will in 20 seconds more cause switch 196 to close but this is ineffective since the switch 192 is open and the energizing circuit to the solenoids is broken. In 30 seconds more, heater 167' will cause switch 167 to open and stop the burner. Manual resetting of switches 167, 192, and 196 will then be required.

Should the nozzle 9 fail during a normal run of the burner, the contacts 178 will be opened, shortly after cessation of combustion, to stop the burner. Then, after the one minute scavenging period, the burner will start up again and in 20 seconds the heater 193 will open switch 192, as before described, to cause the nozzle 10 to be connected to operate.

In the control systems described, the parts within the dot-dash rectangle 208' in Fig. 13 constitute one control instrument. That is, the two relays and the several switches operated by them, the transformer 186, the safety switch 167 and the several switches operated by the stack thermostat 151 are all contained within a single small casing, which may be mounted on the stack of the heating apparatus with the sensitive element of the stack thermostat 151 extending into the stack. The room thermostat 115 will be located in the desired room of the house to be heated and wired up to the aforesaid control instrument in the usual way. The selector switch 110 will be located adjacent its actuating thermostat 130 and wired up to said control instrument and to the solenoids 63 and 76 on the burner. The burner motor and ignition transformer are wired up in the usual manner to said control instrument. The ignition transformer may be located within a casing 209', suitably secured to the casting 5, as indicated in Figs. 3 and 5, with the insulators 210' carrying the high tension terminals 211', projecting partly into the air conduit 7, as shown in Fig. 5, to receive the wires

leading to the electrodes 27. The burner, having the improvements of this invention, such as the two nozzles with the control valves, together with the automatic nozzle-selecting means and the automatic means for operating the unselected nozzle briefly during each cycle of operation of the burner, does not appear much different and is not more bulky than an ordinary burner, lacking these improvements. The solenoid valves are added, inconspicuously and compactly, exteriorly of the burner and the nozzle selector switch is added exteriorly of the main control instrument. If the control of Fig. 14 or Fig. 17 is used, the time switches 192 and 193 may be added exteriorly of the main control instrument or included in such instrument as desired.

It will be clear that the invention has provided several improvements which are useful in a variable firing rate burner for house heating service. There is the safety feature, whereby the nozzle which is not selected for operation is operated once during each cycle of operation of the burner. This tends to avoid carbonization of the nozzle that would otherwise be idle. There is also the emergency feature, whereby if one nozzle does become inoperative, the other nozzle can be used in its place. For maximum protection, the burner should include both these features, but it will be obvious that either feature may be used independently of the other if desired. Finally, there are the improvements in the arrangement of solenoid-operated valves for selecting the oil nozzle to be operated and controlling the movement of the air shutter into proper position to correspond with the selected oil nozzle. These last-named improvements will be useful in a variable firing rate oil burner irrespective of whether the above safety and emergency features, either or both, are used.

I claim:

1. In a variable firing rate oil burner apparatus for house heating systems, of the type wherein air and oil for combustion are respectively supplied by a fan to an air conduit and by a pump to one or the other of two oil conduits, each of which terminates in the air conduit with an atomizing nozzle, and valve means are provided for selectively connecting said oil conduits to the pump to secure high or low rates of firing, and the fan and pump are driven by an electric motor which is adapted to be started and stopped by a room thermostat when there is a demand for heat and when such demand is satisfied, respectively; electromagnetic means for actuating the valve means, a primary nozzle selector switch, a primary energizing circuit for the electromagnetic means including the primary selector switch, the latter being movable from one position to another to cause the electromagnetic means to be actuated to connect one or the other nozzle to the pump, a second nozzle selector switch movable with the first selector switch but operating reversely, an alternate energizing circuit for said electromagnetic means including the second selector switch, a third switch, an electromagnet for actuating the third switch, the latter normally adapted to connect the primary energizing circuit to a source of supply and operable when said electromagnet is energized to connect the alternate energizing circuit to said source, a fourth switch opening and closing in response to the presence or absence of combustion, and a circuit for the electromagnet including the fourth switch and said room thermostat.

2. In a variable firing rate oil burner appa-

ratus for house heating systems, of the type wherein air and oil for combustion are respectively supplied by a fan to an air conduit and by a pump to one or the other of two oil conduits, each of which terminates in the air conduit with an atomizing nozzle, and valve means are provided for selectively connecting said oil conduits to the pump to secure high or low rates of firing, and the fan and pump are driven by an electric motor which is adapted to be started and stopped by a room thermostat when there is a demand for heat and when such demand is satisfied, respectively; electromagnetic means controlling the actuation of said valve means and operable when energized and deenergized to move said valve means to connect one or the other of said oil conduits to said pump, a primary nozzle selector switch, an electromagnet-operated two-position switch, an electromagnet for actuating the last-named switch, a primary energizing circuit for said electromagnetic means including in series both said switches, said selector switch being movable from one position to another to make or break said circuit and cause the valve means to be positioned for the operation of one or the other of said nozzles, said electromagnet operated switch being normally in one position wherein it is closed in said circuit, a second nozzle selector switch movable with the first selector switch but acting reversely to break and make when the first selector switch respectively makes and breaks, an alternate energizing circuit for said electromagnetic means including the second selector switch and said electromagnet-operated switch when in its second position, a normally closed switch opening in response to combustion at the burner, an energizing circuit for said electromagnet including said room thermostat switch and said combustion responsive switch, whereby on a demand for heat from the burner the electromagnet is energized to move its switch from its first to its second position, thereby opening the primary energizing circuit and closing the alternate energizing circuit to the electromagnetic means to cause a reversal of said valve means and the operation of the nozzle not selected by the normal nozzle selector switch, said combustion responsive switch operable on establishment of combustion to open the circuit to said electromagnet, causing its switch to move back to normal position and establish the primary energizing circuit to said electromagnetic means, whereby the valve means is moved back to cause the operation of the nozzle selected by the primary nozzle selector switch.

3. In a variable firing rate oil burner apparatus for house heating systems, of the type wherein air and oil for combustion are respectively supplied by a fan to an air conduit and by a pump to one or the other of two oil conduits, each of which terminates in the air conduit with an atomizing nozzle, and valve means are provided for selectively connecting said oil conduits to the pump to secure high or low rates of firing, and the fan and pump are driven by an electric motor which is adapted to be started and stopped by a room thermostat when there is a demand for heat and when such demand is satisfied, respectively; electromagnetic means controlling the actuation of said valve means and operable when energized and deenergized to move said valve means to connect one or the other of said oil conduits to said pump, a selector switch having one terminal connected to one terminal of said electromagnetic means and having a second

and supply terminal, said selector switch being movable from one position to another to make or break a connection between said terminals, a second switch movable with the selector switch and also having one terminal connected to said electromagnetic means and having a second and supply terminal, said second switch being movable to break or make a connection between its said terminals when the selector switch respectively makes and breaks its said connection, a third switch normally connecting two terminals one of which is connected to the supply terminal of the selector switch, the other terminal of the third switch and the other terminal of said electromagnetic means being adapted for connection to a source of electricity, said third switch having a third terminal connected to the supply terminal of the second switch, an electromagnet controlling the third switch, a circuit for such electromagnet adapted to be closed when the room thermostat starts said motor, said electromagnet being operable when energized to move the third switch to connect with its third terminal and disconnect the supply from the selector switch and connect it to the second switch, whereby the valve means may be reversed to change the firing rate from that for which the selector switch is set, a switch in the circuit of said electromagnet, and means responsive to combustion to open the last-named switch to de-energize said electromagnet and allow the third switch to move to its normal position and connect the supply source to the selector switch, whereby the valve means is moved back to change the firing rate to that for which the selector switch is set.

4. In a variable firing rate oil burner apparatus for house heating systems, of the type wherein air and oil for combustion are respectively supplied by a fan to an air conduit and by a pump to one or the other of two oil conduits, each of which terminates in the air conduit with an atomizing nozzle, and valve means are provided for selectively connecting said oil conduits to the pump to secure high or low rates of firing, and the fan and pump are driven by an electric motor which is adapted to be started and stopped by a room thermostat when there is a demand for heat and when such demand is satisfied, respectively; electromagnetic means controlling the actuation of said valve means and operable when energized and deenergized to move said valve means to respectively connect the oil conduit of the low firing rate nozzle and the oil conduit for the high firing rate nozzle to said pump, a primary nozzle selector switch, an electromagnet-operated two-position switch, an electromagnet for actuating the last-named switch, a primary energizing circuit for the electromagnetic means including in series both said switches, said selector switch being movable from one position to another to make or break said circuit and cause the valve means to be positioned for low or high rate firing, said electromagnet-operated switch being normally in one position wherein it is closed in said circuit, a second nozzle selector switch movable with the first selector switch but acting reversely to break and make when the first selector switch respectively makes and breaks, an alternate energizing circuit for the electromagnetic means including the second selector switch and said electromagnet-operated switch when the latter is in its second position, a normally closed switch opening in response to combustion at the burner, an energizing circuit for said electromagnet

net including said room thermostat switch and said combustion responsive switch, whereby on a demand for heat from the burner the electromagnet is energized to move its switch from its first to its second position, thereby opening the primary energizing circuit and closing the alternate energizing circuit to the electromagnetic means to cause a reversal of said valve means and the operation of the nozzle not selected by the primary nozzle selector switch, said combustion responsive switch operable on establishment of combustion to open the circuit to said electromagnet, causing its switch to move back to normal position and establish the primary energizing circuit to the electromagnetic means, whereby the valve means is moved back to cause the operation of the nozzle selected by the primary nozzle selector switch.

5. In a variable firing rate oil burner apparatus for house heating systems, of the type wherein air and oil for combustion are respectively supplied by a fan to an air conduit and by a pump to one or the other of two oil conduits, each of which terminates in the air conduit with an atomizing nozzle, and valve means are provided for selectively connecting said oil conduits to the pump to secure high or low rates of firing, and the fan and pump are driven by an electric motor which is adapted to be started and stopped by a room thermostat when there is a demand for heat and when such demand is satisfied, respectively; electromagnetic means controlling the actuation of said valve means and operable when energized and deenergized to move said valve means to connect one or the other of said oil conduits to said pump, a nozzle selector switch, an energizing circuit for said electromagnetic means including said selector switch, the latter being movable from one position to the other to make or break said circuit and cause the valve means to be positioned for the operation of one or the other of said nozzles, a heat-actuated time switch in said circuit operable when heated for a predetermined time to open and break said circuit, an electric heating element for said time switch, an energizing circuit for said element, a switch in the last-named circuit opening and closing by the presence or absence of combustion at the burner, whereby when said selector switch is positioned to make the first-named energizing circuit and cause the valve means to be positioned for operation of one nozzle and combustion does not occur within said predetermined time, the time switch will open and break the energizing circuit to said electromagnetic means deenergizing the latter and causing the valve means to be moved into position for operation of the other nozzle.

6. In a variable firing rate oil burner apparatus for house heating systems, of the type wherein air and oil for combustion are respectively supplied by a fan to an air conduit and by a pump to one or the other of two oil conduits, each of which terminates in the air conduit with an atomizing nozzle, and valve means are provided for selectively connecting said oil conduits to the pump to secure high or low rates of firing, and the fan and pump are driven by an electric motor which is adapted to be started and stopped by a room thermostat when there is a demand for heat and when such demand is satisfied, respectively; electromagnetic means controlling the actuation of said valve means and operable when energized and deenergized to move said valve means to connect one or the other of said oil con-

duits to said pump, a nozzle selector switch, an energizing circuit for said electromagnetic means including said selector switch, the latter being movable from one position to the other to make or break said circuit and cause the valve means to be positioned for the operation of one or the other of said nozzles, an independent energizing circuit for said electromagnetic means excluding said selector switch, a heat-actuated time switch in the last-named circuit normally open but operable when heated for a predetermined time to close, an electric heating element for said time switch, an energizing circuit for said heating element excluding said selector switch and closed when the room thermostat closes to start the burner, a switch in the last-named circuit opening and closing by the presence or absence of combustion at the burner; whereby when the selector switch is set to break the first-named energizing circuit, causing the valve means to be positioned for operation of one of said nozzles, and combustion does not occur within said predetermined time the time switch will close the independent energizing circuit, causing the latter to be energized to move the valve means into position for operation of the other of said nozzles.

7. In a variable firing rate oil burner apparatus for house heating systems, of the type wherein air and oil for combustion are respectively supplied by a fan to an air conduit and by a pump to one or the other of two oil conduits, each of which terminates in the air conduit with an atomizing nozzle, and valve means are provided for selectively connecting said oil conduits to the pump to secure high or low rates of firing, and the fan and pump are driven by an electric motor which is adapted to be started and stopped by a room thermostat when there is a demand for heat and when such demand is satisfied, respectively; electromagnetic means controlling the actuation of said valve means and operable when energized and deenergized to move said valve means to connect one or the other of said oil conduits to said pump, a nozzle selector switch, an energizing circuit for said electromagnetic means including said selector switch, the latter being movable from one position to the other to make or break said circuit and cause the valve means to be positioned for the operation of one or the other of said nozzles, a heat-actuated time switch in said circuit operable when heated for a predetermined time to open and break said circuit, an electric heating element for said time switch, an energizing circuit for said heating element, a switch in the last-named circuit opening and closing by the presence or absence of combustion at the burner; whereby, when the selector switch is positioned to make the first-named energizing circuit and cause the valve means to be positioned for operation of a first one of said nozzles and combustion does not occur within said predetermined time, the time switch will open and break the energizing circuit to said electromagnetic means, deenergizing the latter and causing the valve means to be moved into position for operation of the other and second one of said nozzles; a second heat-actuated time switch normally open but operable when heated for a predetermined time to close, an alternate energizing circuit for said electromagnetic means including both time switches and excluding the selector switch, an electric heating element for the second time switch, an energizing circuit for the last-named heating element excluding the selector switch and closed when the room thermostat closes to

start the burner, a switch in the last-named circuit opening and closing by the presence or absence of combustion at the burner; whereby when the selector switch is set to break the first-named energizing circuit and cause the valve means to be positioned for operation of the second one of said nozzles and combustion does not occur within said predetermined time, the second time switch will close the alternate energizing circuit for said electromagnetic means energizing the latter and causing the valve means to be moved into position for operation of the first one of said nozzles.

8. In a variable firing rate oil burner apparatus for house heating systems, of the type wherein air and oil for combustion are respectively supplied by a fan to an air conduit and by a pump to one or the other of two oil conduits, each of which terminates in the air conduit with an atomizing nozzle, and valve means are provided for selectively connecting said oil conduits to the pump to secure high or low rates of firing, and the fan and pump are driven by an electric motor which is adapted to be started and stopped by a room thermostat when there is a demand for heat and when such demand is satisfied, respectively; an air valve movable from one position to another to increase or decrease the rate at which air is supplied by said fan to said air conduit, a spring normally holding the air valve in its position of greater opening, a hydraulic motor operable when supplied with pressure fluid to move the air valve to its position of lesser opening, an electromagnet controlling the actuation of said valve means and operable when energized and deenergized to position the valve means to respectively connect the low firing rate nozzle and high firing rate nozzle to said pump, an energizing circuit for said electromagnet, a selector switch in said circuit to open and close the same and cause the valve means to connect the high firing rate nozzle and low firing rate nozzle respectively to said pump, a conduit from the pressure side of the pump to said motor and controlled by said valve means, said conduit adapted to be opened and closed as the valve means is respectively positioned to connect the low firing rate nozzle and high firing rate nozzle to the pump, a conduit connection from said motor to the suction side of the pump, a valve in said connection, and a second electromagnet in said circuit operable when energized and deenergized to respectively close and open said connection.

9. In a variable firing rate oil burner apparatus for house heating systems, of the type wherein air and oil for combustion are respectively supplied by a fan to an air conduit and by a pump to one or the other of two oil conduits, each of which terminates in the air conduit with an atomizing nozzle, and valve means are provided for selectively connecting said oil conduits to the pump to secure high or low rates of firing, and the fan and pump are driven by an electric motor which is adapted to be started and stopped by a room thermostat when there is a demand for heat and when such demand is satisfied, respectively; said valve means comprising a two-way solenoid-actuated valve, said solenoid operable when energized and deenergized to move the valve into position to respectively connect the conduit for the low firing rate nozzle and the conduit for the high firing rate nozzle to said pump, an energizing circuit for said solenoid and a switch in the circuit for opening and closing the same, an air valve movable from one position to another to increase or decrease the rate at which air is supplied by the

fan to said air conduit, a spring for moving the air valve to its position of greater opening, a hydraulic motor for moving the air valve to its position of lesser opening, a conduit connecting the oil conduit for the low firing nozzle to said motor, whereby oil is admitted to the motor to move the air valve to its position of lesser opening when the two-way valve is positioned to connect the oil conduit for the low firing rate nozzle to the pressure side of said pump, a conduit for connecting the motor to the suction side of said pump, a second solenoid actuated valve having its solenoid connected in parallel with the solenoid of the first-named valve and operable when its solenoid is energized and deenergized to respectively close and open said suction conduit.

10. In a variable firing rate oil burner apparatus for house heating systems, of the type wherein air and oil for combustion are respectively supplied by a fan to an air conduit and by a pump to one or the other of two oil conduits, each of which terminates in the air conduit with an atomizing nozzle, and valve means are provided for selectively connecting said oil conduits to the pump to secure high or low rates of firing, and the fan and pump are driven by an electric motor which is adapted to be started and stopped by a room thermostat when there is a demand for heat and when such demand is satisfied, respectively; said valve means comprising a two-way solenoid-actuated valve, said solenoid operable when energized and deenergized to move the valve into position to respectively connect the conduit for the low firing rate nozzle and the conduit for the high

firing rate nozzle to said pump, an energizing circuit for said solenoid and a switch in the circuit for opening and closing the same, an air valve movable from one position to another to increase or decrease the rate at which air is supplied by the fan to said air conduit, a spring for moving the air valve to its position of greater opening, a hydraulic motor for moving the air valve to its position of lesser opening, a conduit connecting the oil conduit for the low firing rate nozzle to said motor, whereby oil is admitted to the motor to move the air valve to its position of lesser opening when the two-way valve is positioned to connect the oil conduit for the low firing rate nozzle to the pressure side of said pump, a conduit for connecting the motor to the suction side of said pump, and a second solenoid-actuated two-way valve operable when its solenoid is energized and deenergized to respectively close and open said suction connection by one way and to respectively open and close the oil conduit for the low firing rate nozzle by the other way in addition to the opening and closing effected by the first-named valve.
